UNITED STATES PATENT OFFICE

169,484

ASH TRAY

Carl F. Herdecker, North Attleboro, Mass., assignor to Evans Case Co., North Attleboro, Mass.

Application November 28, 1952, Serial No. 22,482

Term of patent 14 years

(Cl. D85—2)

To all whom it may concern:

Be it known that I, Carl F. Herdecker, a citizen of the United States, residing in North Attleboro, in the county of Bristol and State of Massachusetts, have invented a new, original, and ornamental Design for an Ash Tray, of which the following is a specification, reference being had to the accompanying drawing, forming part thereof.

Figure 1 is a top plan view of an ash tray embodying my new design;

Figure 2 is a side elevation thereof; and

Figure 3 is an end elevation thereof.

I claim:

The ornamental design for an ash tray, as shown.

CARL F. HERDECKER.
